UNITED STATES PATENT OFFICE.

CHARLES MILLS AND LOREN W. PENNEY, OF NEWTON, MASSACHUSETTS,
ASSIGNORS TO THE SACO & PETTEE MACHINE SHOPS, OF SAME PLACE.

DRAWING-FRAME.

SPECIFICATION forming part of Letters Patent No. 638,975, dated December 12, 1899.

Application filed August 2, 1898. Serial No. 687,532. (No model.)

To all whom it may concern:

Be it known that we, CHARLES MILLS, of Newton Upper Falls, and LOREN W. PENNEY, of Newton Highlands, in the county of Middlesex and State of Massachusetts, have invented certain new and useful Improvements in Drawing-Frames, of which the following is a description sufficiently full, clear, and exact to enable those skilled in the art to which it appertains or with which it is most nearly connected to make and use the same.

This invention has relation to that class of machinery employed in the preparation of textile fibers for the operation of spinning, commonly known as "drawing-frames" or "drawing-machines," employed chiefly for the purpose of improving the parallelizing of the fibers and the equalization of the weight and thickness of the slivers treated thereby.

It is the object of the invention to so improve an organized drawing-frame as that the principal purposes thereof may be carried out more efficiently, economically, and conveniently than heretofore.

In the disclosure of the invention as will hereinafter appear a description will be given of the structural character of the improvements created and the mode of their operation will also be set forth, and in connection therewith, where it is necessary, the advantages gained and mischiefs or objections overcome will also be stated.

Reference is to be had to the annexed drawings, and to the letters marked thereon, forming a part of this specification, the same letters designating the same parts or features, as the case may be, wherever they occur.

Of the drawings, Figure 1 is a plan view, partially in section, of so much of a drawing-machine as it is necessary for the purposes of this specification to show, the said drawing-machine being equipped with our improvements. Fig. 2 is a plan view of a portion of the rear roller of the pair of delivery-rollers detached, showing our improvements so far as they are connected therewith. Fig. 3 is a vertical cross-sectional view taken through the upper part of a drawing-machine provided with our improvements. Fig. 4 is a partially-sectional view of a trumpet and its adjuncts and some of its co-operating parts,

as will more fully appear hereinafter. Fig. 5 is a diagrammatic view, in side elevation, of a stand for supporting the gearing for operating the rollers of the several heads in a drawing-machine. Fig. 6 is a plan view of the stand and most of the gearing, as well as the pulleys for operating the gearing. Fig. 7 is a plan view, on enlarged scale, of one of the coiler mechanisms, together with a trumpet and appurtenances. Fig. 8 is a sectional detail view of a coiler-tube gear, its driving-gear, and some of the associated parts.

In the drawings, *a* designates the fixed supporting means of the machine, which may be called the "frame."

b designates the drawing-rolls, arranged in "sections" or "deliveries" and receiving the material to be operated upon from the feed-rollers *c*, back of which is the guide-plate *d*.

The parts so far described form no part of our present invention, and therefore may be of the form shown or any other suited to the purpose for which they are used.

e designates the front calender-roller, one being required for each section or delivery, the journals of which rollers are loose in their bearings, as usual, so as to afford play to the rollers in directions to and from the rear driving calender-roller *f*, which is made in one piece extending the length of the frame. We make the rear calendering-roller *f* smaller in diameter than the front rollers and arrange the pair of rollers so as that the lowest lines of their peripheries shall be upon substantially the same horizontal plane in order that when viewed from above the rear roller will appear to be and to all intents and purposes will be lower than the front roller. This construction, for one thing, enables us to cant the trumpet *h* in such manner that the sliver passing from the drawing-rollers to the calender-rollers may extend upon a more nearly direct line than though the trumpet were held in level position, the latter arrangement resulting in advantages obvious to those skilled in the art, chief among which is the vertical delivery of the slivers into the tube of the coiler-gear.

Where two calender-rollers of the same size are arranged with their axes in the same horizontal plane, the sliver coming from the

drawing-rollers is required to make too sharp a bend into the trumpet, which with this arrangement of calender-rollers necessarily stands vertically over the bight between the latter. On the other hand, if the calender-rollers are arranged obliquely to allow a disposition of the trumpet which will avoid the abrupt bend of the sliver, the latter will be shot forward instead of delivered directly downward. To overcome the above-mentioned difficulties, it has been customary to employ three rollers, the two calender-rollers set obliquely and the third being a guiding-roller to direct the sliver straight downward into the coiler-tube. By our arrangement above described the extra roller is dispensed with, while all the advantages of the three-roller arrangement are retained. As above stated, the reduction in diameter of the rear calender-roller, while its lowest peripheral line is kept in a horizontal plane embracing the lowest peripheral line of the larger front roller, provides for sufficient canting of the trumpet to avoid too sharp a bend of the sliver. Again, although the axes of the two rollers and the line of contact between them are in an oblique plane, yet the sliver will be delivered directly downward, owing to the fact that the large front roller is longer in contact therewith than is the small rear roller, it being borne in mind, in this connection, that the sliver expands immediately after passing the line of contact between the rollers.

We construct the driving calender-roller *f* preferably of one solid piece of steel, turning down the same at intervals to form bearing-necks and cut gear-teeth *i* on the end of each section, as shown, which gear-teeth *i* engage the teeth of the gears *j*, secured on the ends of the front rollers. The gear-teeth *i* are shortened to their pitch-line relatively to the teeth of the gears *j* with which they mesh. Under this improvement the front roller is disengaged from the driving means of the rear roller and delivery is stopped before a comparatively great amount of fiber becomes wound thereon and before delivery would be stopped under the construction in common use. This is a matter of much importance, since if the machine is not stopped quickly after the fiber commences to wind on the rollers serious mischief results. Again, it is more advantageous and economical to cut the teeth upon the roller *f*, as we do, than to make the gear in halves and pin said halves on the roller, as was necessary heretofore with the inner gears, since they could not be slipped on from the end of the roller, and in addition to this the gears *i*, as we form them, are more durable than those heretofore formed, since it is obvious that if the teeth were long or of full length they would be more likely to be broken by reason of their subjection to greater strain. Moreover, by making the rear roller smaller, as we do, and cutting the teeth *i* thereon, as described, more space is left at the end of the roller for the employment of a greater range

of change-gearing for preserving the right tension upon the sliver.

k designates the main gear-stand, which is provided with a flanged base *l*, whereby provision is made for bolting or otherwise securing it to the top of the roller-beam *m*, so that when once secured in place it becomes to all intents and purposes one with the beam. The main gear-stand above its base may be made of a flat piece of metal, milled on both of its sides and on its foot, so that it is easy and economical to make and finish, besides being otherwise advantageous, as will presently appear.

The main or leading feature of our improved main gear-stand is that it is so constructed as to adapt it to carry all of the end bearings and gearing necessary for driving all of the rolls and the front coiler-shaft, whereas under former constructions of this kind it required two or three separate stands to accomplish the same purpose, which former stands had to be removed or separately adjusted when any roll or gear was taken off or adjusted.

The stand is provided with a curved slot *n* in form concentric with the axis of the shaft *o*, having affixed upon it the driving-gear *p*, one end of the slot *n* being enlarged, as at *q*. By this means when it is necessary to change the speed of the calender or finishing rollers the nut for securing the journal-stud of the change-gears *r* in place may be loosened, the said stud moved up to the enlarged point *q* of the slot, the stud and gear removed, another gear or gears substituted, and the parts returned to and secured in place without disturbing the stand, and the work can readily be done by one person. The form of the slot *n* provides for keeping the gear *s²* in proper mesh with the driving-gear *p* and also for adjusting the gear *r* (which is fastened on the hub of the gear *s²*) into requisite mesh with the coiler-shaft gear *s* on the end of the coiler-shaft *d'*, which gear *s* is a change-gear for varying speed to suit different sizes of coiler-cams.

The calender-rollers, it will be understood, are driven from the change-gear *r* (which is practically compounded with the gear *s²*) through the medium of the coiler-shaft gear *s* and the idler *s'* meshing with the gear *t* on the back calender-roller. The gears *s s'* for the sake of clearness are omitted from Fig. 6.

The draft-gear *u*, which is also a change-gear, has its journal-stud supported in a bracket *v*, which is adjustable on the main-gear stand by means of a bolt *w*, which may move in a slot *x*, formed in the bracket, which slot is curved in form concentric with the driving-shaft, as shown. The bracket *v* is on the driving-shaft, so that it can be swung concentrically therabout, keeping the crown-gear *y* (with which the draft-gear *u* is compounded) in proper mesh with the driving-wheel and also allowing the draft-gear *u* to be brought into proper mesh with the gear which it drives.

The removable and change gearing are arranged, as is necessary to a practical and economical construction, on the same side of the stand as that from which the rollers extend. This improvement is important, since, as before shown, it is economical and efficient, permits the work to be done by one person without removing the stand, and allows any gear to be taken out without removing the others.

z z' designate fast and loose pulleys, from which the machine is operated and by which it is governed.

a' designates the front half of the cover for

15 the coiler-tube gear b', the support b" for which cover and gear extends out over the coiler-can c' and is rabbeted at c" to accommodate the lower edge of the front half of the cover. The front half of the said cover is made removable, while the back half a" is stationary. This construction enables us to readily remove the front half a' of the cover by simply lifting it off and placing it to one side around the adjacent cover, as is shown in Fig. 1, (a 25 portion of the front calendering-roller being represented as broken away to better show the construction,) in order to get in to correct anything in connection with the coiler-tube gear or to remove the latter or any of its 30 connections. The back part of the cover connects with adjacent covers, all of the joints being close and the upper surfaces smooth, so that neither dust nor lint can get below the covers and so that the surfaces can easily be 35 cleaned by "dusting" or brushing. Heretofore in case the sliver passing through the coiler-tube gear should "bung up" or in case of other similar mishap it was necessary to remove the entire cover and generally the 40 gear also to set things right.

d' designates the coiler driving-shaft, arranged below the covers a" and provided at each head with a small bevel-gear e', which meshes with a like bevel-gear f', set into and 45 connected with the hub g', Fig. 8, of a gear h', which meshes with and drives the coiler-tube gear b'. The hubs of the gears f' and h' turn on a stud i', set into the frame-plate, and the latter is countersunk to provide a 50 bearing for the rim j of the hub g', so that the said countersink may be freely supplied with a lubricant and the overflow therefrom may flow over to the recess formed in the plate for the rim-bearing k' of the coiler-tube gear.

55 By the construction just described the parts are brought close together vertically in order that they may be made compact, be easily lubricated, and otherwise made efficient and ready of access.

60 The pivoted arm l' of the trumpet is provided on its under side with an adjusting-screw m', Fig. 4, which supports the trumpet in position by resting upon a pivoted lever n', the latter in turn resting upon the coiler-gear 65 or its cover, so that as the coiler-can becomes filled and raises the coiler-gear the trumpet will be raised and the machine will be stopped.

By adjusting the trumpet as described it becomes unnecessary to change the same for various grades of work, as heretofore.

The usual stopping mechanism is shown in Fig. 3, on which the arm of the trumpet acts through the medium of the usual contrivances to stop the machine.

In Fig. 1 we have shown the front half of 75 the cover to one coiler-gear as removed and placed around and over the front part of the coiler-gear next to the right. This gives opportunity for free access to the coiler-gear and its adjuncts in an easy and convenient 80 way.

We may repeat that we regard the single main gear-stand as a very important part of our invention, since in addition to what has already been said of it it leaves room for a 85 greater range or extent of change-gearing and allows of the same being easily and quickly adjusted and secured in place.

Having thus explained the nature of the invention and described a way of constructing 90 and using the same, though without attempting to set forth all of the forms in which it may be made or all of the modes of its use, it is declared that what is claimed is—

1. In a drawing-machine, the combination 95 with an obliquely-set trumpet; of front and rear calender-rollers, the rear one being appreciably smaller than the front one and the lowest peripheral lines of the two rollers being in substantially the same horizontal plane. 100

2. A calendering-roller for fiber-treating machines constructed from a single length of metal, turned down at intervals to form necks or journals to form sections, each section having a plain face, and provided with teeth at 105 one end integral with the roller.

3. The combination, with a sectional roller for fiber-treating machines provided with gears secured thereon, of a coöperating sectional roller made from a single length of 110 metal, and having gear-teeth cut thereon at the end of each section with which the teeth of the gears on the first-mentioned roller mesh.

4. The combination, with the front sectional calendering-roller of a fiber-treating machine 115 and gears secured thereon, of the rear coöperating sectional roller, smaller in diameter than the front roller, made from a single length of metal and having gear-teeth cut on one end of each section with which the teeth 120 of the gears on the first-mentioned roller mesh, the outer end of the teeth formed on the rear roller terminating on their pitch-line.

5. In a machine of the character described, the combination with the roller-beam, driving-shaft, calender-roller and coiler-shaft of a one-piece gear-stand erected on said beam and having a bearing for the driving-shaft and a forward overhanging portion with bearings for the calender-roller and coiler-shaft; 125 a gear supported by said stand and connecting the said shafts with provisions for change, substantially as described.

6. In a machine of the character described,

the combination with the roller-beam, driving-shaft, calender-roller and coiler-shaft of a one-piece gear-stand erected on said beam and having a bearing for the driving-shaft 5 and a forward overhanging portion with bearings for the calender-roller and a coiler-shaft, said stand having a curved slot concentric with the driving-shaft; and gears supported by said stand and connecting the said shafts 10 and including a compound whose stud occupies said curved slot, substantially as and for the purpose described.

7. In a machine of the character described, the combination with the roller-beam and 15 driving-shaft; of a one-piece gear-stand erected on said beam and having a bearing for the driving-shaft and a forward overhanging portion with bearings for a calender-roller and a coiler-shaft; gears supported 20 by said stand and connecting the said shafts with provisions for change; a supplementary stand or bracket straddling the driving-shaft and slotted concentrically therewith; clamping means associated with said slot for securing said bracket to the main stand; and 25 change-gearing carried by the bracket for transmitting motion from the driving-shaft to certain of the drawing-rollers, substantially as described.

8. A stand for the gearing and rollers of a fiber-treating machine consisting of a substantially flat piece of metal adapted to be secured to the roller-beam, provided with a hole or aperture for the driving-shaft and a 35 short curved slot n distant therefrom concentric with the hole, the said slot having an enlargement q at one end.

9. In a fiber-treating machine, the combination of a roller-beam; a horizontal supporting-plate extending forward therefrom; a coiler-gear cover-section fixedly associated 40 with said beam and plate and extending over the rear half of the gear-space; and a detachable and removable front half or section 45 completing the cover and engaging the supporting-plate, substantially as described.

10. In a fiber-treating machine, the combi-

nation of a roller-beam; a horizontal supporting-plate extending forward therefrom; coiler-gear cover-sections fixedly associated 50 with said beam and plate and fitted together end to end; and detachable and removable front halves or sections completing the covers and engaging the supporting-plate, substantially as described. 55

11. In a drawing-machine, the combination, with a rim-bearing coiler-gear, of a supporting frame-plate provided with a groove to receive the said rim, and a countersink adjacent thereto, a driving-gear h' having its 60 bearing-hub seated in said countersink, and means to provide for the overflow of the lubricant from the countersink into the groove of the bearing for the coiler-tube gear.

12. The driving-gear h' provided with a 65 bearing-hub, combined with a support for the hub countersunk to receive said hub, a gear f' to impart motion to the driving-gear set in the face of the latter and affixed thereto, and a stud or pin upon which the said gears turn. 70

13. The combination, with the coiler driving-shaft d' , a bevel-gear s thereon, and the coiler-gear, of a support for the coiler-gear and the gear h' for driving the same, provided with a countersink in which the hub 75 of the said driving-gear is set, and a bevel-gear f' set in the face of the driving-gear and meshing with the bevel-gear on the driving-shaft.

14. The combination, with the lever n' , of 80 the trumpet-arm l' provided on its under side with an adjusting-screw m' resting upon the said lever and forming a support for the trumpet-arm, to adjust the trumpet and co-operate with the stopping mechanism. 85

In testimony whereof we have signed our names to this specification, in the presence of two subscribing witnesses, this 11th day of July, A. D. 1898.
